UNITED STATES PATENT OFFICE.

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SOLES.

Application filed January 24, 1920. Serial No. 353,819.

The present invention relates to machines for operating upon shoe soles prior to their incorporation in boots or shoes.

One object of the present invention is to provide novel and improved mechanism for guiding and feeding shoe soles to the operating instrumentalities of a machine and for disposing of the soles at the completion of the operation.

Another object of the present invention is to provide mechanism of this type which is particularly adapted to be embodied in a sole molding machine so that the machine as a whole will be relatively simple and compact in construction, and efficient in operation.

To these ends the invention provides a novel organization comprising a magazine for soles, means for feeding them severally to handling mechanism and thence to operating instrumentalities. In the disclosed machine the soles are fed sidewise from the magazine and thence longitudinally to a position between molds, and ejected from the molds after the molding operation. The soles are fed through the molds, being ejected from the side opposite to that into which they are fed. The ejecting means is actuated by the molds themselves in opening after the molding operation.

Features of the invention further consist in certain constructions, arrangements and combinations of parts hereinafter described and claimed, the advantages of which will be obvious to those skilled in the art from the following description.

The preferred embodiment of the present invention is illustrated in the accompanying drawings in which:

Figure 1 is a right side elevation of a sole molding machine embodying the several features of the present invention in their preferred form; Fig. 2 is a rear elevation on an enlarged scale partly broken away to save space; Fig. 3 is a plan view of the rear portion of the machine; Fig. 4 is a detailed bottom plan view of side gages for positioning a sole laterally; Fig. 5 is a vertical sectional view taken on the line 5—5 of Fig. 3; Fig. 6 is an enlarged sectional plan view taken on the line 6—6 of Fig. 5; Fig. 7 is an enlarged

vertical sectional view taken on the line 7—7 of Fig. 5; Figs. 8 and 9 are vertical sectional views similar to Fig. 5 showing the operating parts of the feeding mechanism of the machine in different positions which they assume during the operation of the machine; Fig. 10 is a vertical section of a forward portion of the machine showing the cooperating molds in molding position with the sole held between them, and a portion of the feeding mechanism; Fig. 11 is a similar view of the portion of the feeding mechanism illustrated in Fig. 10 with the operating parts of the mechanism shown in the position they assume during the separation of the molds; Fig. 12 is a detailed section taken on the line 12—12 of Fig. 11; Fig. 13 is a plan view partly in section of the portion of the machine illustrated in Fig. 10 with the upper mold removed; Fig. 14 is a detailed sectional plan of a clutching device taken on the line 14—14 of Fig. 10; Fig. 15 is a front elevation of a portion of the forward end of the feeding mechanism to illustrate a toe gage; Fig. 16 is a vertical section on an enlarged scale taken on the line 16—16 of Fig. 1; Fig. 17 is a side elevation of the sole ejecting mechanism shown as about to remove the sole from between the molds which are indicated by broken lines; Fig. 18 is a vertical section taken approximately on the line 18—18 of Fig. 17; and Fig. 19 is a section taken on the line 19—19 of Fig. 18.

The present invention is embodied in a sole molding machine which is provided with two sets of cooperating molds adapted to work alternately. As the two sets of molds and their associated mechanisms are of the same general construction and mode of operation, only one set of molds and its associated mechanism is illustrated in the drawings and specifically described herein.

The soles to be operated upon by each set of molds are contained in a magazine from which the soles are severally delivered onto a table, and after being properly positioned upon the table as hereinafter described, they are transferred lengthwise to the molds. When a sole has been thus presented to the molds, it is firmly held in position during the molding operation and at the completion of

this operation the sole is discharged from the molds. The magazine and table are located at the rear of the molds with the magazine arranged above and at one side of the table, the soles being delivered sidewise from the magazine and the molded soles being discharged from the front of the molds. With this construction, it will be seen that the machine is as compact as possible and takes up a minimum amount of floor space, and the molds and magazine are conveniently accessible to the operator.

The molds of each set are arranged so that their heel ends are directed toward the rear of the machine and comprise cooperating upper and lower molds 2 and 4 respectively, (Fig. 1) the upper mold being relatively fixed and the lower mold being movable toward and from the upper mold. The lower mold is thus actuated by means of a toggle 6 connected through a link 8 with a crank 9 carried by a shaft 10. The crank shaft 10 is continuously driven through a gear 12 carried thereby which operatively engages a gear 14 carried by the driving shaft 16 of the machine.

In the illustrated machine the magazine for containing the soles to be operated upon, indicated at 18, (Figs. 1 and 2) is supported by vertically adjustable brackets 19 secured to the frame of the machine. The soles are delivered sidewise from the magazine through an opening 20 at the bottom of the inner wall thereof by means of a pusher or ejector 22. The ejector 22 comprises a plate mounted to slide upon the bottom wall of the magazine having its outer end pivotally connected to the upper end of an arm 24, the lower end of which arm is secured to a rock shaft 26. The rock shaft 26 is actuated to cause a sole to be ejected from the magazine near the limit of the downward movement of the lower mold 4, by means of an arm 28 having one end secured to the rock shaft and its other end provided with a roll engaging a cam slot 30 in an arm 32 projecting from the carrier for the lower mold.

The magazine 18 is located above and to one side of a table 34 upon which the soles drop by gravity as they are delivered from the magazine. The table 34 comprises plates secured to the frame of the machine. When a sole is thus delivered to the table 34 it is first positioned laterally and then angularly relatively to the molds and is then positioned longitudinally to bring its longitudinal center in a definite position relatively to the longitudinal center of the molds. The sole is then clamped in position and transferred a fixed distance to a position between the molds. By thus positioning the sole on the table and transferring it to the molds, the proper positioning of the sole between the molds is assured irrespective of the width or the length of the sole. The means for thus positioning

and transferring the sole to the molds has the same construction and mode of operation, except as hereinafter described, as the machine illustrated and described in United States Letters Patent No. 1,491,284, granted April 22, 1924, on application of Lewis J. Bazzoni, to which reference may be had for a full and complete description of the parts of the machine not fully described herein.

The soles delivered to the table 34 are positioned laterally thereon by means of gages 36 (Figs. 2 to 5) which engage opposite sides of the sole. The gages 36 comprise arms projecting from sleeves or hubs 38 pivotally mounted on vertical pins 40 mounted in a bracket 41 projecting from the magazine 18. The gages 36 are connected to move simultaneously toward and from each other by means of intermeshing gear segments 42 projecting from the hubs 38. The gages are urged toward each other to engage the sole by means of a coiled spring 44 having its ends connected to lugs 46 projecting from the hubs 38. The gages 36 are held separated sufficiently to permit the sole to be delivered from the magazine to the table by the engagement of a latch 48 with a downwardly extending arm 49 projecting from one of the hubs 38. The latch 48 comprises a lever pivoted at 50 on the bracket 41 projecting from the magazine 18. The latch 48 is urged in a direction to maintain its forward end in locking engagement with the arm 49 by means of a torsion spring 52, this movement of the latch being limited by a stop pin 54 on the bracket 41. When the sole has been delivered to the table, the latch 48 is released to permit the gages to be moved by their spring 44 into engagement with the sides of the sole to position the sole laterally. The releasing of the latch is accomplished at this time by the engagement of a cam block 56 (Fig. 5) with the rear end of the latch, the cam block being movable toward and from the molds by means hereinafter described, and the engagement of the cam block and latch occurring near the limit of the movement of the cam block away from the molds.

The means for angularly and longitudinally positioning the sole comprises gaging devices hereinafter described, actuated by a transferring slide 58 (Figs. 2 and 5) upon which the cam block 56 is mounted. The transferring slide is mounted in ways 62, the table 34 forming the forward portion of the upper gibs of the ways. The transferring slide is initially moved a distance dependent upon the length of the sole toward the molds from the position shown in Fig. 5, by which movement the gaging devices are actuated to position the sole angularly and longitudinally. The transferring slide is then moved a fixed distance to transfer the sole to the desired position between the molds. The transferring slide is actuated by means of a slide 130

64 mounted in ways 66 beneath the transferring slide. The connection between the slides 58 and 64 to effect the initial movement of the transferring slide comprises a lug 68 5 carried by the actuating slide 64 which engages the rear side of the lower end of a downwardly curved member 70 of a forked arm 72 which constitutes one arm of a three arm lever 74 pivotally mounted on a horizontal pin 76 secured to the transferring slide.

The three arm lever 74 is held stationary at this time to maintain the end of the member 70 in engagement with the lug 68 against 15 the action of a coiled spring 78 engaging the rear end of the lever 74, by means of a latch lever 80 pivoted at 82 on the transferring slide 58, which extends through an aperture in the rear arm of the lever 74 and engages 20 a shoulder formed on the upper side of the arm, the latch lever being held in position by a coiled spring 81 connected with the lower end thereof. During the first part of the initial movement of the transferring slide, 25 the sole is positioned angularly on the table 34 by a V-shaped heel gage 84 (Figs. 5 and 13) mounted on the transferring slide 58 which is brought into engagement with the heel end of the sole. The heel gage 84 comprises 30 a pair of oppositely disposed arms 86 that are pivotally mounted on vertical screws threaded into bosses on the transferring slide. The arms 86 are connected to move simultaneously in opposite directions by means 35 of intermeshing gear teeth 88 formed on the hubs of the arms. The arms are urged toward each other by means of a coiled spring 90 interposed between rearwardly projecting lugs 92 on the arms, and this movement of 40 the arms is limited by means of a pin 94 having one end pivotally secured to one lug 92 and its other end extending through an aperture in the other lug and provided with a stop nut threaded on its end.

45 At the completion of the angular positioning of the sole, the heel gage 84 cooperates with a toe gage 96 to position the sole longitudinally, the toe gage being moved toward the sole and heel gage, at the same rate of speed as the movement of the heel gage, thereby positioning the sole to bring its longitudinal center in a definite position on the table 34 irrespective of the length of the sole. The toe gage 96 (Figs. 8 and 15) is of the 50 construction illustrated and described in said Patent No. 1,491,284. The toe gage is swung upwardly and is moved toward the sole by means of a rack 102 mounted to slide on the frame of the machine and operated by a pinion 100 driven by a rack 98 which is actuated by engagement of a shoulder 104 on the lower end of the member 70 of the three armed lever 74 with a transverse arm 106 (Figs. 6 and 7) carried by the rear end of 55 the rack.

When the sole has been thus positioned upon the table 34, the movement of the transferring slide 58 toward the molds is arrested and the sole is held in position by a gripping device carried by the transferring slide 58. To this end when the sole has been positioned longitudinally, the continued movement of the transferring slide 58 acts to spread the sole engaging arms of the heel gage sufficiently so that a pivoted finger 108 70 projecting upwardly between the arms is brought into engagement with the sole. The finger 108 is pivoted on the transferring slide and when engaged by the sole (Fig. 9) the upper end thereof is swung rearwardly, 80 which, through a link 110 connecting the lower end thereof with the lower end of the latch lever 80 immediately disengages the latch lever from the three arm lever 74, the spring 78 of the three arm lever being then 85 permitted to turn the lever in a direction to disengage the member 70 from the lug 68, thereby disengaging the slide 58 from the actuating slide 64. This movement of the three arm lever 74 also disengages the end of 90 the member 70 from the end of the toe gage actuating rack 98, whereupon the toe gage is returned to its initial position by means of a weight 111 (Fig. 1) connected by a cord to the rear end of the rack, the rearward movement of the rack being limited by engagement with a stop lug 113. The sole is then gripped between a jaw 112 constituting one arm of the lever 74 and a stationary jaw 114 mounted on the feed slide 58 as illustrated 95 in Fig. 9.

In order that the transferring slide 58 may be moved a fixed distance toward the molds after its described initial movement, a measuring bar 116 is employed which, 100 during the initial movement of the transferring slide, is held stationary and at the end of this movement is locked in position to the transferring slide. The continued movement of the actuating slide 64 moves a 110 member thereof into engagement with the measuring bar so that the two slides are again connected and the transferring slide moved in unison with the actuating slide toward the molds. The measuring bar 116 extends through an aperture in the lower end of a depending arm 117 of the three armed lever 74 and is in sliding engagement therewith. During the initial movement of the transferring slide the bar 116 is held stationary by the engagement of a lug 118 (Fig. 8) formed thereon with a shoulder 120 on a latch lever 122 pivoted upon the frame of the machine, the latch lever being held in position against a stop 119 by a 115 spring 121. When the three arm lever 74 is swung in a direction to arrest the initial movement of the transferring slide, the measuring bar is thereby moved to disengage the lug 118 from the latch lever 122, 120

(Fig. 9) whereupon the measuring bar is locked in position to the three arm lever 74. The locking of the measuring bar 116 to the three arm lever is accomplished by a locking device comprising an eccentric 124 pivoted upon the depending arm 117, which, when the lever 74 is swung in the direction to grip the sole is turned to firmly grip the measuring bar by means of a coiled spring 126 connected to the free end of an arm 128 projecting from the eccentric 124. During the initial movement of the transferring slide, the eccentric is held out of locking engagement with the measuring bar by means of a lug 129 (Fig. 9) projecting upwardly from the arm 128 and engaging the under side of the transferring slide. The transferring slide is moved to convey the sole to the molds after the measuring bar 116 is locked to the three arm lever 74 by the engagement of an adjustable abutment screw 130, threaded through a lug 132 on the actuating slide 64, with the rear end of the measuring bar.

During the first part of the final movement of the transferring slide toward the molds, the side gages 36 are disengaged from the sole so that they will not interfere with the delivering of the next sole to be operated upon to the table. In the illustrated machine the gages 36 are disengaged from the sole at this time by the engagement of the cam block 56 with a depending lug 133 (Fig. 4) projecting from the hub of one of the arms of the gages. This permits the latch 48 to snap into locking engagement with the arm 49, so as to maintain the gages in open position after the cam block 56 passes by the lug 133.

When the sole has been positioned between the molds, the transferring movement of the slides 58 and 64 is arrested, and in order that the sole may continue to be held in proper position between the molds during the molding operation, there is provision for moving the transferring slide 58 upwardly with the lower mold while the gripping device 112-114 continues to grip the sole. To this end, the forward portion of the guideway for the transferring slide 58 is formed in a casting 134 (Figs. 10 and 16) which is mounted to slide vertically in guideways 136 in the frame of the machine. The positioning of the sole between the molds occurs during the upward movement of the lower mold, and just before the lower mold is in position to engage the sole the casting 134 is connected to the lower mold so that the casting and the transferring slide carrying the sole are moved upwardly in unison with the lower mold. The casting 134 is connected to the lower mold at this time by the engagement of a pair of lugs 138 projecting from the lower mold carrier with shoulders 140 formed on the casting 134. In order to fur-

ther insure that the sole will be properly held in position during the molding operation, an auxiliary gripping device engages the sole during the upward movement of the lower mold to cooperate with the gripping device mounted on the transferring slide. This auxiliary gripping device comprises a gripping member 142 rigidly secured to the lower mold support or carrier for engaging the bottom side of the sole and a cooperating yielding gripping member 144 mounted in the portion of the frame that supports the upper mold, for engaging the top of the sole. The lower gripping member 142 is provided with a bifurcated head and a shank 146 that is adjustably secured in an aperture in the carrier of the lower mold by means of a screw 148. The upper gripping member is provided with a corresponding bifurcated head and a shank 150 that extends through an aperture 152 in a boss 153 on a portion of the frame of the machine that supports the upper mold. The gripping member 144 is yieldingly urged downwardly by means of a spring 154 coiled about the shank 150 and interposed between a collar on the shank and a shoulder 156 near the upper end of the aperture 152. The downward movement of the gripping member 144 is limited by the engagement of a nut 158 threaded on the upper end of the shank 150 with the upper end of the boss 153. In order to vary the gripping action of the gripping member 144, the tension of the spring 156 may be adjusted by adjusting the nut 158 on the shank 150.

When the lower mold is retracted at the completion of the molding operation, the lugs 138 allow the transferring slide 58 to drop by gravity to its initial position, this movement of the transferring slide being limited by the engagement of stop shoulders 160, Fig. 16, on the casting 134 with shoulders on the frame of the machine. During this downward movement of the transferring slide, the auxiliary gripper 142-144 and the gripping device 112-114 mounted on the transferring slide will continue to grip the sole until it has thereby been stripped from the molds. As the transferring slide approaches the limit of this movement, the gripping device 112-114 is released from the sole. To this end, a stop arm 164 is mounted upon the jaw arm of the three arm lever 74 which stop arm during the downward movement of the transferring slide engages the end of a bracket 166 secured to the inner wall of the magazine, as shown in Fig. 11, which causes the three arm lever to be moved in a direction to open the jaws.

In order that during the upward movement of the transferring slide the stop arm 164 may pass by the bracket 166, the stop arm is pivotally mounted upon the lever 74

and is urged upwardly against a stop lug 165 (Fig. 12) by a torsion spring 167.

When the transferring slide 58 has reached the limit of its downward movement, the return or rearward movement of the actuating slide 64 is initiated. Shortly after the start of this return movement, the slide 64 picks up the transferring slide 58 to return the latter to its initial position at 10 the rear of the machine. This is accomplished by means of a shoulder formed on the upper end of the lug 132 on the slide 64, being brought into engagement with a shoulder on a lug 168 projecting rearwardly 15 from the transferring slide 58, whereupon the slide 58 is moved in unison with the actuating slide 64 to its initial position.

In order that the lug 68 on the actuating slide 64 may clear the end of the depending 20 arm 70 of the three arm lever 74 during the first part of the return movement of the actuating slide before the lugs 132 and 168 become engaged, the three arm lever 74, while being turned sufficiently to release the 25 sole during the downward movement of the transferring slide at the completion of the molding operation, is not turned sufficiently at this time to position the end of the abutment member 70 in the path of the lug 68. 30 After the lug 68 has passed by the end of the member 70, the lever 74 is further turned a sufficient distance so that the lug 68 will engage the member 70 upon the next movement of the actuating slide 64 toward the 35 molds. This additional turning movement of the lever 74 is accomplished by the stop arm 164 riding over an upwardly inclined protuberance 170 (Fig. 11) on the stop bracket 166. The lever 74 is then locked in 40 position by the engagement therewith of the latch lever 80. During the return movement of the slides, the measuring bar 116, which has been released by the final turning movement of the lever 74, is stopped from movement with the slides when the stop lug 118 thereon reaches the shoulder 120 on the latch 122, by the engagement of the stop lug with a depending finger 174 on the end of the latch 122. By the time the slides have 45 reached the limit of their retracting movement another sole has been delivered from the magazine on the table 34 and at the extreme limit of this movement of the slides, the side gages 36 are released by the cam block 56 engaging the rear end of the latch lever 48 as previously described, and the 50 cycle of operations of the machine is repeated.

In order that during the retracting movement of the feed slides the end of the member 70 of the three arm lever 74 may pass by the abutment arm 106 on the rear end of the toe gage actuating rack 98 so that the member 70 may engage the arm during the 55 next advancing movement of the slides, the

arm 106 is pivotally mounted on the end of the rack and is held in position against a stop by a torsion spring 177, Fig. 6. With this construction, when the member 70 engages the arm 106 during the retracting movement of the slides, the arm will be depressed thereby and when the member 70 passes by the arm, the latter will snap into position.

In the illustrated machine the lower slide 75 64 is actuated toward and from the molds in timed relation to the retraction of the molds, as above described, by connection with the driving shaft of the machine (Figs. 1, 2 and 8). This connection comprises a 80 pair of gears 178 mounted on shafts 180 beneath the actuating slide 64 which gears are driven in unison. First one gear 178 acts through a rack 182 secured on the under side of the slide 64 to move the slide and then 85 the rack 182 is picked up by the other gear 178 to move the slide the remainder of its movement toward or from the molds. The gears 178 are connected to rotate in unison by a sprocket chain 184 that passes over 90 sprocket wheels secured to the shafts 180. The gears 178 are driven by means of a pinion 186 secured to the forward shaft 180 that is engaged by a segmental gear 188 formed on the upper end of a lever 190 pivoted at 192 on the frame of the machine. The lever 190 is actuated by the engagement of a cam roll 194 on the lower end thereof with a cam groove 196 formed in one face of a gear 198 that is mounted on a shaft 100 200 journaled in bearings in the frame of the machine. The gear 198 is driven through pinions 202 which connect the gear with the gear 12 carried by the crank shaft 10.

Immediately after the gripping device 105 142-144 associated with the molds and the gripping device 112-114 associated with the transferring slide have stripped the molded sole from the molds, an ejecting device acts to grip the sole and convey it forwardly 110 from between the molds allowing it to drop into a receptacle placed in front of the machine. This ejecting device comprises a sole gripping device (Figs. 17 to 19) mounted on a sliding carrier 208 which in turn is 115 mounted to slide on a rearwardly and upwardly inclined guide bar 210 that is secured at its ends to a bracket 212 on the frame of the machine and arranged at the left side of the molds. The gripping device is provided with a stationary lower jaw 214 secured to the carrier 208 and a self adjusting jaw 216 pivotally mounted upon the inner end of a lever 218. The lever 218 is pivoted at 220 on the sliding carrier 208 and 125 is urged in a direction to cause the jaw 216 to cooperate with the jaw 214 to grip the sole by means of a torsion spring 222. During the upward movement of the lower mold, the jaws 214 and 216 are opened to 130

6
 permit the sole to pass between them on its passage to a position between the molds and at the completion of the molding operation, as the sole is stripped from the molds, the 5 jaws are permitted to close on the sole. The jaws are opened by means of a tail piece 224 on the lever 218 over which extends the free end of a substantially horizontal arm of a lever 226 pivoted on the bracket 212. The lever 226 is urged in a direction to move the end of its arm upwardly away from the tail piece 224 to permit the torsion spring 222 to close the jaws on the sole, by means of a coiled spring 228 having one end connected to the arm, this movement of the lever 226 being limited by a stop pin 230 on the bracket 212. The lever 226 is swung in a direction to open the jaws at the proper time by the engagement of an inclined surface 10 on the upper end of a post 232 adjustably secured to the carrier for the lower mold, with a roll 234 on a depending arm of said lever 226. During the retraction of the lower mold the disengagement of the post 232 from the roll 234 permits the jaws to 15 close upon the sole. The carrier 208 is then moved forwardly on the guide bar 210 to convey the sole forwardly from between the molds and near the limit of this movement 20 the jaws 214-216 are opened to permit the sole to drop by gravity from the machine. The opening of the jaws is accomplished at this time by the engagement of the tail piece 224 on the jaw carrying lever 218 with an 25 inclined surface 236 on a lug projecting from the bracket 212. The carrier 208 is then immediately returned to its initial position at the rear of the molds to permit the jaws 214-216 to engage the next sole 30 that is molded. The carrier 208 is actuated through connections with a sprocket chain 238 that passes over sprockets 240 located respectively at the front and rear of the molds. The sprocket 240 located at the front of the 35 molds is mounted on a shaft 242, and the sprocket located at the rear of the molds is carried by a shaft 244. The connection between the carrier 208 and the sprocket chain 238 is such that both the sole ejecting and 40 the retracting movements of the carrier are accomplished by one complete rotation of the chain. This connection comprises a block 246 secured to the carrier which is provided with a substantially vertical slot 45 that is engaged by a stud 248 secured to one of the links of the chain 238 so that as the chain is carried around the sprocket wheels the stud 248 will freely work in the slot.

The mechanism for thus driving the 50 sprocket chain 238 comprises a sprocket chain 250 (Figs. 10, 14 and 17) that passes over a sprocket wheel secured to the shaft 244 and a sprocket wheel 252 formed on the driven member 254 of a clutching device. 55 The member 254 is loosely mounted on a con-

stantly rotating shaft 256 driven by a sprocket and chain 258 which may be connected to the driving shaft of the machine. The clutch member 254 is urged toward the driving clutch member 260 secured to the 70 shaft 256 by means of a spring 262 coiled about the shaft and interposed between the outer end of the clutch member 254 and a collar secured to the shaft. The clutch member 254 is held out of engagement with the member 260 by the engagement of the end 75 of a horizontal bolt 264 with a cam lug 266 formed on the member 254. The bolt 264 is mounted to slide in ears 268 projecting from the frame of the machine, and the bolt 80 is urged toward the clutch member 254 by means of a spring 270 coiled about the bolt between the rear ear 268 and a collar secured to the bolt. The clutching device is provided with means for retracting the bolt 264 85 from the cam lug 266 to allow the clutch members to become engaged by the action of the clutch spring 262, and at the completion of one rotation of the sprocket chain 250 to release the bolt 264 allowing it to re-engage the cam lug 266 thereby disconnecting the clutch members, the clutch being thrown in at the proper time during the downward movement of the lower mold. The means 90 for retracting the bolt 264 comprises an arm 272 having one end pivotally mounted on a pin 274 and its other end engaging a pin 276 projecting laterally from the bolt. A second arm 278 is also pivotally mounted on the pivot pin 274. The arms 272 and 278 are urged in opposite directions about the pivot pin 274 by means of a coiled spring 280 interposed between the arms and such relative movement of the arms is limited by the engagement of abutment lugs 281 on the 95 hubs of the arms. At the proper time during the downward movement of the lower mold, an inwardly projecting lug 283 on the end of a depending finger 282 mounted on the under side of the lower mold carrier engages a lug 285 on the free end of the arm 278 which acts through the lugs 281, arm 272, and pin 276 to retract the bolt from engagement with the cam lug 266 on the driven member against the action of its spring 270. 100 When the bolt 264 has been thus retracted, the arm 278 has been swung a sufficient distance to the rear to disengage the lug 285 from the lug on the end of the finger 282, allowing the end of the finger to pass by the end of the arm. The lock bolt is then held in retracted position by an upwardly spring 105 pressed plunger 284, the end of which snaps up into engagement with the end of the bolt 264 when the bolt is disengaged from the cam lug 266. At the completion of one revolution of the sprocket chain a lug 286 carried thereby engages a pin 288 projecting laterally from the plunger 284 to retract the 110 plunger from engagement with the bolt 264 115 120 125 130 135

thereby allowing the bolt to be moved by its spring into engagement with the cam lug 266 to disengage the clutch members. During the upward movement of the lower 5 mold, the yielding connection between the arms 272 and 278 permits the end of the finger 282 to pass by the end of the arm 285. Upon the next downward movement of the lower mold, the clutch will again be thrown 10 in as above described to repeat the cycle of operations of the sole ejecting device.

While the features described above are well adapted for use in a sole molding machine, it is to be understood that, except as 15 defined in the claims, the features of the invention are not limited to use in a machine of this type.

The nature and scope of the present invention having been indicated and a machine 20 embodying the several features of the invention in their preferred form having been described, what is claimed is:—

1. A machine for operating upon soles having, in combination, operating instrumentalities, a sole magazine, means for feeding a sole horizontally sidewise completely out of contact with the remaining soles in the magazine, means for clamping the sole on its top and bottom faces, and means for feeding the clamped sole lengthwise into position to be operated upon by said instrumentalities and for thereafter operating upon the sole with said instrumentalities.

2. A machine for operating upon soles 35 having, in combination, a pair of cooperating molds, a sole magazine, means for severally feeding the soles sidewise from the magazine and then lengthwise to a position between the molds, and means for ejecting the individual soles from the molds at the completion of the molding operation.

3. A machine for operating upon soles having, in combination, operating instrumentalities, a sole magazine, means for severally feeding the soles sidewise from the magazine until entirely out of contact with the remaining soles, means for locating a sole thus delivered from the magazine both laterally and longitudinally, means for clamping the sole in located position, and means for then feeding the sole lengthwise toward the position of the operating instrumentalities prior to the operation of said instrumentalities thereon.

4. A machine for operating upon soles having, in combination, a pair of cooperating molds, and means comprising a sole gripping device oscillating between the molds and engaging the sole subsequent to the molding operation for ejecting the sole from the molds.

5. A machine for operating upon soles having, in combination, a pair of cooperating molds for molding a sole, and a device 65 engaging opposite sides of the sole and work-

ing between the molds for ejecting the sole from the molds at the completion of the molding operation.

6. A machine for operating upon soles having, in combination, a pair of cooperating molds for molding a sole, and means comprising a sole gripping device engaging the sole at one side of the molds to eject the sole from the opposite side of the molds at the completion of the molding operation. 75

7. A machine for operating upon soles having, in combination, upper and lower molds for molding a sole, relatively movable supports for said molds, means comprising members mounted on the mold supports for stripping the sole from the molds at the completion of the molding operation, and independent means for ejecting the sole from the molds. 80

8. A machine for operating upon soles having, in combination, a pair of cooperating molds for molding a sole, a carrier, a sole gripping device mounted on the carrier, and means for actuating the gripping device at the completion of the molding operation 90 to grip the sole, for then actuating the carrier to convey the sole from between the molds, and for then actuating the gripping device to release the sole.

9. A machine for operating upon soles having, in combination, a pair of cooperating molds, means for feeding a sole to the molds, means to actuate relatively the molds to mold the sole, and mechanism independent of said feeding means thrown into operation by actuation of the molds after the completion of the molding operation to engage the sole and eject it from the molds. 95

10. A machine for operating upon soles having, in combination, upper and lower 100 molds, relatively movable supports for said molds, means for actuating the lower mold toward and from the upper mold to mold a sole placed between the molds, and cooperating members arranged at one side of the 110 molds comprising a downwardly spring-pressed gripping member mounted on the upper mold support and a member mounted on the lower mold support to grip the sole during the molding operation and to strip 115 the sole from the molds at the completion of the molding operation.

11. A machine for operating upon soles having, in combination, a pair of cooperating molds, means comprising a sole gripping 120 device located at one side of the molds for delivering a sole to a position between the molds and for holding the sole in position during the molding operation, and means for ejecting the sole from the opposite side 125 of the molds at the completion of the molding operation.

12. A machine for operating upon soles having, in combination, upper and lower molds, means for moving the lower mold to- 120

ward and from the upper mold, a sole gripping device, and means for actuating the gripping device to position the sole between the molds and then to move the gripping device upwardly with the lower mold and to release the gripping device during the retraction of the lower mold.

13. A machine for operating upon soles having, in combination, upper and lower molds, means for moving the lower mold toward and from the upper mold, a magazine, means actuated by movement of the lower mold for feeding a sole sidewise from the magazine, and means for then feeding the sole lengthwise to a position between the molds.

14. A machine for operating upon soles having, in combination, upper and lower molds, means for moving the lower mold toward and from the upper mold, a magazine, a member for delivering a sole sidewise from the magazine, and connections between said member and the lower mold for actuating said member comprising a bell crank lever having one end pivotally connected to said member and its other end operatively connected to the lower mold.

15. A machine for operating upon soles having, in combination, operating instrumentalities, a magazine, means for delivering a sole sidewise from the magazine, and means for then feeding the sole lengthwise toward the operating instrumentalities a distance automatically determined by the length of the sole.

16. A machine for operating upon soles having, in combination, operating instrumentalities, a magazine, means for delivering a sole sidewise from the magazine, and means including devices for automatically gaging the length of the sole to feed the sole lengthwise toward the operating instrumentalities a distance dependent upon the length of the sole.

17. A machine for operating upon soles having, in combination, a pair of cooperating molds, a sole gripping device and means for actuating the sole gripping device to feed a sole to a position between the molds, to hold the sole in position during the molding operation, then to release the sole, and then to move away from the sole.

18. A machine for operating upon soles having, in combination, a table, a transferring slide, means for delivering a sole to the table, gages for engaging opposite sides of the sole to position the sole laterally after it is delivered to the table, means for actuating the slide to feed the sole, a cam block carried by the slide and movable between the gages, and means actuated by the cam block for disengaging the gages from the sole during the feeding movement of the slide.

19. A machine for operating upon soles

having, in combination, a transferring slide, means for actuating the slide to feed a sole delivered thereto, gages connected to move simultaneously to position a sole laterally, and means comprising a member connected with the gages and an actuating cam block therefor carried by the slide for separating the gages during the feeding movement of the slide.

20. A machine for operating upon soles having, in combination, a transferring slide, means for actuating the slide to feed a sole delivered thereto, gages connected to move simultaneously toward and from each other to position the sole laterally, means for retracting the gages from the sole and for maintaining the gages retracted during a portion of the feeding movement of the slide comprising a member carried by one of the gages and a latch cooperating with said member to maintain the gages retracted, and means for releasing the latch.

21. A machine for operating upon soles having, in combination, a pair of cooperating molds, means for relatively actuating the molds, means comprising a feed slide for conveying a sole to the molds, a cam, a gear segment actuated by the cam, and connections between the gear segment and feed slide for actuating the feed slide in timed relation to the actuation of the molds.

22. A machine for operating upon soles having, in combination, operating instrumentalities, a sole magazine, a table out of contact with the soles in the magazine, means for delivering a sole sidewise from the magazine to the table, gaging devices for positioning the sole on the table, other devices for holding the sole in gaged position, and means for feeding the sole thus held lengthwise toward the position of the operating instrumentalities preparatory to the operation of said instrumentalities thereon.

23. A sole molding machine having, in combination, a pair of cooperating molds for molding the sole, and a gripping device working back and forth between the molds from one side to the other for ejecting the sole from the molds at the completion of the molding operation.

24. A sole-molding machine having, in combination, a pair of co-operating molds, a sole magazine arranged to hold a vertical pile of soles, means for severally feeding the soles sidewise to separate them completely from the remaining soles in the magazine, means for positioning the soles comprising fingers arranged to contact with their edges, means arranged to contact with the plane faces of the soles to hold them in position, and means for feeding the soles lengthwise to a position between the molds while they are thus held.

25. A sole molding machine having, in combination, upper and lower molds, a sole

magazine, and means for feeding a sole laterally from the magazine and then longitudinally to the molds comprising means actuated by one of the molds for delivering a sole from the magazine.

26. A sole-molding machine having, in combination, a pair of co-operating molds, a sole magazine arranged to hold a pile of soles, means for feeding a sole laterally out of the magazine into a position in longitudinal alinement with the molds, and means for then feeding the sole lengthwise into position to be operated upon by the molds.

27. A machine for operating upon soles having, in combination, a pair of co-operating relatively movable molds for molding a sole between them, a device for gripping a sole and feeding it into position between said

molds and for holding it gripped during the molding operation, and mechanism responsive to relative separating movement of the molds after the molding operation to cause said gripping device to release the sole.

28. A machine for operating upon soles having, in combination, a pair of co-operating relatively movable molds for molding a sole between them, a device for gripping a sole and feeding it into position between said molds and for holding it gripped during the molding operation, means for retracting said gripping device from the molds after the molding operation, and automatic means for causing said device to release the sole prior to its retractive movement.

LEWIS J. BAZZONI.
